UNITED STATES PATENT OFFICE.

WILLIAM T. BOOTH, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-TRANSMITTER.

1,352,939.

Specification of Letters Patent. Patented Sept. 14, 1920.

Application filed February 24, 1917. Serial No. 150,632.

To all whom it may concern:

Be it known that I, WILLIAM T. BOOTH, a citizen of the United States, residing at East Orange, in the county of Essex and 5 State of New Jersey, have invented certain new and useful Improvements in Telephone Transmitters, of which the following is a full, clear, concise, and exact description.

This invention relates to telephone transmitters and the like, and more particularly to a means for sealing the working parts of such apparatus against the entrance of moisture.

The invention provides a unitary structure comprising a front plate or mouthpiece member on which the working parts of the transmitter, for example, are mounted. The diaphragm and damping spring construction are preferably of the general type disclosed 20 in the Scribner Patent 1,050,304, dated January 14, 1913, inasmuch as this construction does not require the perforation of the diaphragm at its center, which had been considered necessary in previous 25 constructions, to permit the attachment of the front electrode of the transmitter button to the diaphragm.

The invention further provides a gasket which is clamped between the periphery of 30 the diaphragm and the supporting front plate or mouthpiece in such a way as to prevent the entrance of moisture from the mouthpiece under the edge of the diaphragm. This gasket extends beyond the 35 edge of the diaphragm a sufficient distance so that when the transmitter unit is placed in the external moistureproof casing, the gasket will also engage the rim of the casing and act as a seal against the entrance of 40 moisture at this point.

Other features of the invention will appear from a consideration of the accompanying drawings, which show one form of the invention as applied to an incased transmitter, and in which Figure 1 is a side view 45 partly in cross-section of the transmitter, while Fig. 2 is a horizontal cross-section thereof.

The construction shown comprises a cylindrical casing 1 of brass or other suitable material, having the bottom thereof closed. The top edge 2 of the casing is smooth and preferably beveled toward the outer edge. The casing has a threaded portion at the top 55 thereof. Trunnions 4 are shown on opposite

sides of the casing 1, and serve to facilitate pivotal mounting of the casing if desired, and are secured to the casing in such a way as to make a water-tight joint therewith. The trunnions may obviously be formed integral with the casing if desired. A water-tight push button 5 is mounted in the casing, which also carries a stuffing box 6, through which conductors (not shown) leading to the incased apparatus extend. The stuffing box 6 comprises a collar 7, which may be either separate from or integral with the casing 1, and which has an outwardly beveled bore 8, in which is seated a soft rubber wedge 9. A cap 10 is threaded to the collar 7, and carries a metallic washer 11, which prevents abrasion of the rubber on movement of the cap. Tightening of the cap forces the wedge 9 into firm engagement with the cord extending through the stuffing box 6, and thus produces a water-tight joint therewith.

The transmitter mechanism is assembled and placed within the casing 1 as a single unit, which greatly facilitates inspection and adjustment of the apparatus. The arrangement shown comprises a ring 12 of any suitable material, preferably brass, which carries a transmitter bridge 13 secured to the rear thereof. The bridge carries a transmitter button 14 insulated therefrom. The button 14 is held in contact with an imperforate diaphragm 15, by a central damping spring 16 secured to but insulated from one leg of the bridge 13. This construction is of the general type disclosed in Scribner Patent No. 1,050,304, of January 14, 1913, and is peculiarly adapted to the requirements of a water-tight construction in that it does not necessitate the perforation of the diaphragm for the attachment of the transmitter button and the danger of moisture entering through the diaphragm is thereby eliminated. Adjustment of the button 14 with reference to the diaphragm 15 is accomplished by providing a collar 17 carried by but insulated from the bridge and in which the stem 18 of the button 14 is longitudinally movable. A set screw 19 in the collar 17 engages the stem 18 to hold it in its adjusted position.

The diaphragm 15 is shown as separated from the ring 12 by a ring 20 preferably of oiled muslin, and an annular washer or gasket 21 of suitable moisture proof cush-

- ioning material, preferably rubber, engages the upper edge of the diaphragm and makes a water-tight joint therewith. A mouth-piece 22 is secured to the ring 12 by a series 5 of screws 23, and serves to press the gasket 21 into firm engagement with the diaphragm 15 to hold the diaphragm firmly in position, and to provide a water-tight joint between the diaphragm and the washer 21.
- 10 This joint serves to keep moisture entering the mouthpiece 22 from penetrating to the rear of the diaphragm. A suitable drain opening 24 may be provided in the mouth-piece 22 to furnish an outlet for any moisture which may collect behind the mouth-piece.
- 15 It is often desirable to have a transmitter cut-out or cut-in button, and provision is made for a cut-in button in the construction 20 shown. The back of the bridge 13 is provided with a fixed contact piece 25, insulated therefrom, and having a plurality of arms 26 and 27; the arms having stops to limit the outward movement of contact springs 25 28 and 29 respectively. The springs 28 and 29 are secured to, but insulated from the sides of the bridge 13. The spring 28, while insulated from the bridge 13, is electrically connected with the damping spring 16 30 through screws 30, while the spring 29 is connected to the binding post 31 in a similar manner. The spring 28 is separated from the arm 26 by insulation 32, while the spring 29 normally makes electrical contact 35 with the arm 27, as shown. The ring 12 has a slot 33, to which a pin 34 on the casing 1 fits, to position the unit in proper relation to the push button 5, as shown; the spring 28 engaging with the insulated tip of the push 40 button. The springs 28 and 29 are arranged to make engagement before contact is broken between the arm 27 and spring 29; while insulation 35 on the contact piece 25 prevents electrical contact between the spring 29 and contact piece 25 on forcing the push-button 45 into its limit of movement. Contact piece 25 carries a binding post 36, and the normal circuit extends in over the binding post 31, thence to spring 29, to arm 27, and thence 50 out through binding post 36, leaving the transmitter button 14 short-circuited; while, on pressing the push button 5, the transmitter button 14 is placed in circuit for transmission, the circuit extending in over the binding post 31, thence to spring 29, spring 28, screws 30, damping spring 16, transmitter button 14 and stem 18 to collar 17, and thence out over binding post 37, which is in 55 electrical contact with the collar.
- 60 The annular gasket 21 is part of the unitary transmitter structure and bears upon the upper edge 2 of the casing 1, while a locking ring 38 engaging over a peripheral flange of the mouthpiece 22 serves to hold

the unitary structure in place, and to make a 65 water-tight joint between the washer 21 and the casing 1. The single washer 21 thus serves to seal against moisture entering either by way of the upper edge of the casing or by way of the mouthpiece and dia- 70 phragm, while the assembling of the washer, as a part of the unitary structure, is of considerable advantage.

The invention is obviously also suitable 75 for telephone receivers or other devices wherein it is desirable to hold a diaphragm or the like in place, and also to provide a seal between the diaphragm mounting and a surrounding support or casing.

What is claimed is:

1. In combination, a casing open at one end, diaphragm supporting means, a front plate, a diaphragm between said supporting means and plate, said diaphragm being smaller than the internal dimensions of the 85 open end of said casing, a gasket of moisture proof cushioning material engaging the periphery of said diaphragm and extending beyond the same into engagement with the open end of said casing to prevent moisture 90 entering said casing, and means to secure said front plate to the open end of said casing.

2. A casing for acoustic apparatus comprising a cup, a diaphragm supported with- 95 in the cup, a cover for the casing, and a moisture proof gasket providing moisture proof joints between the cover and cup and between the diaphragm and cup.

3. A casing for acoustic apparatus comprising a cup, a cover therefor, a diaphragm supported within the cup having one side thereof substantially flush with the rim of the cup, a gasket of moisture proof cushioning material between said cover and casing 100 engaging the periphery of the diaphragm and the rim of the open end of said cup providing moisture proof joints between the cup and cover and between the diaphragm and cup.

4. In combination, a casing open at one end, diaphragm supporting means, a front plate, a diaphragm smaller than the internal dimensions of the open end of said casing located between said front plate and sup- 115 porting means, a telephonic element within said casing and adjacent said diaphragm, a gasket of moisture proof cushioning material engaging the periphery of said dia- phragm and the open end of said casing 120 to prevent moisture entering said casing, and means to secure said front plate to the open end of said casing.

5. A transmitter casing comprising a cup, a cover therefor, a diaphragm supported 125 within the cup, a transmitter element within said casing in engagement with said dia- phragm, and a gasket of moisture proof

5 cushioning material between said cover and cup engaging the periphery of said diaphragm and the rim of the cup to provide moisture proof joints between the cup and cover and between the diaphragm and cup.

6. In combination, a casing open at one end, diaphragm supporting means, a front plate, an imperforate diaphragm between said supporting means and front plate, a 10 transmitter element within said casing, means for holding said element in engagement with said diaphragm, a gasket of moisture proof cushioning material engaging the periphery of said diaphragm and the open end of said casing to prevent moisture entering said casing, and means to secure said front plate to the open end of said casing.

7. The combination with a unitary telephonic element, of a casing therefor open at one end, and means to secure said element to the open end of said casing; said unitary element comprising a transmission device, supporting means therefor, a diaphragm 25 smaller than the internal dimensions of the open end of said casing to coöperate with said device and carried by said supporting means, and a gasket of moisture proof cushioning material engaging said diaphragm and the open end of said casing to prevent moisture entering said casing.

8. The combination with a unitary telephonic element, of a casing therefor open at one end, and means to secure said element to the open end of said casing; said unitary element comprising a transmission device, supporting means therefor, a diaphragm smaller than the internal dimensions of the open end of said casing to co-
35 operate with said device and carried by said supporting means, a front plate, and a single gasket of moisture proof cushioning material between said front plate and supporting means, said gasket also engaging the open

end of said casing to prevent moisture entering said casing. 45

9. In combination, a casing open at one end, diaphragm supporting means, a mouthpiece, an imperforate diaphragm between said supporting means and mouthpiece, a 50 transmitter element within said casing, a spring engaging said transmitter element to hold it in contact engagement with the inner side of said diaphragm, a gasket between said mouthpiece and diaphragm engaging the periphery of said diaphragm and the open end of said casing, and means to secure said mouthpiece to the open end of said casing. 55

10. In combination, a casing having a 60 substantially circular opening at one end, a diaphragm smaller than said opening and supported therein, a front plate covering said opening, a single gasket of moisture proof cushioning material engaging the periphery of said diaphragm and also engaging said casing and front plate to make a moisture tight joint therebetween, and means to secure said front plate to said casing. 70

11. In combination, a casing open at one end, a ring in the open end of said casing, a bridge carried thereby, a diaphragm carried on said ring within said casing and substantially flush with the rim thereof, a 75 transmitter button carried by said bridge and engaging said diaphragm, a single gasket between said ring and mouthpiece engaging the periphery of said diaphragm and the rim of the open end of said casing, 80 and means to secure said mouthpiece to the open end of said casing and in engagement with said gasket.

In witness whereof, I hereunto subscribe my name this 23rd day of February A. D., 85 1917.

WILLIAM T. BOOTH.
